SIDE DELIVERY RAKEJoe Enos, Jr., Visalia, Calif., assignor to
Melvin A. Morrill, Laton, Calif.

Application May 5, 1949, Serial No. 2,445

Term of patent 14 years

(Cl. D35—2)

To all whom it may concern:

Be it known that I, Joe Enos, Jr., a citizen of the United States, residing at 445 South Bridge Street, in the city of Visalia, county of Tulare, and State of California, have invented a new, original, and ornamental Design for a Support and Draft Apparatus for a Side Delivery Rake, of which the following is a specification, reference being had to the accompanying drawing, forming part thereof.

Fig. 1 is a perspective view of a support and draft apparatus for a side delivery rake, showing my new design.

Fig. 2 is a front elevational view thereof.

Fig. 3 is a rear elevational view thereof.

Fig. 4 is a top plan view thereof.

I claim:

The ornamental design for a support and draft apparatus for a side delivery rake, as shown.

JOE ENOS, JR.
